APPARATUS FOR CHEMICALLY CLEANING
AND DRYING FABRICS, TEXTILES, GAR-
MENTS AND THE LIKE

Georg Wolff, Munich, Germany, assignor to Dr. Alexander Wacker Gesellschaft für Elektro-chemische Industrie, G. m. b. H., Munich, Germany, a corporation

Original application September 13, 1932, Serial No. 632,947. Divided and this application June 6, 1934, Serial No. 729,278. In Germany March 5, 1932

1 Claim. (Cl. 34—5)

This invention relates to apparatus for chemically cleaning and drying fabrics, textiles, garments and the like and is a division of copending application Ser. No. 632,947 filed in the 5 United States September 13, 1932 and in Germany March 5, 1932.

Combined washing and drying machines usually consist of a perforated drum containing the articles, which rotates in a casing partially filled with cleaning fluid. After washing, this fluid is drawn off and the heated air enters through distributing tubes or through the perforations in the drum walls.

This practice is objectionable because the 15 heated air tends to leave the drum near the point of inlet and flow in the channel intermediate the drum and casing. The air is thereby partially lost as far as its drying function is concerned and merely serves to heat the walls 20 to an undesired degree and in an uneconomical manner. The articles are frequently scorched or otherwise damaged if permitted to remain in contact with the heated walls for an appreciable period.

An object of the invention is to improve the 25 construction and operation of rotary washing and drying machines and particularly to prevent damage to the articles being treated, and to accelerate evaporation of the washing fluid and drying of the articles in the apparatus after cleaning.

I have found that with a novel construction, position and arrangement of the inlet and/or outlet passages I am able to prevent prolonged 35 contact between the articles and the metal walls whereby the temperature of the drying medium may be increased and evaporation of the solvent and drying of the articles safely accelerated.

In accordance with the preferred embodiment 40 of the invention, the air is admitted into and/or discharged from the drum in an undivided stream. The passages in the drum wall necessary to pass this stream are preferably quite 45 large and are tapered and slant inwardly so that the washed articles which might otherwise enter these openings are carried by centrifugal force and/or gravity away from the metal and walls.

The novel features characteristic of the present 50 invention are set forth with particularity in the appended claim. The invention itself, however, both as to its organization and method of operation with further objects and advantages, will best be understood by reference to

the following description and to the accompanying drawing, wherein:

Figs. 1 and 2 are, respectively, longitudinal and transverse sections of a machine having enlarged axially arranged inlet and outlet 5 passages;

Figs. 3 and 4 are longitudinal and transverse sections of a machine having an air inlet passage similar to that of Fig. 1 but spaced from the axis of the drum, and an outlet similar to that of 10 my earlier application.

The combined washing and drying machine of Figs. 1 and 2 has a closed casing 1 containing a rotating receptacle or drum 2. The two end walls and the perforated cylindrical wall of the 15 drum are preferably made of sheet metal. Drum 2 is provided at each end with longitudinally extending annular conical passages 3 for air. These passages which surround the axis of the drum are conically widened or flared towards 20 the interior of the drum and are provided with radial bars 4 as shown. Such passages serve to expand the air stream adjacent the inlet and to contract the stream adjacent the outlet, thereby 25 insuring a better distribution and circulation of air through the drum. Articles which might otherwise tend to obstruct these enlarged openings will be checked by radial bars 4 and will slide on the sloping surfaces toward the interior 30 of the drum, thereby preventing prolonged contact between said articles and end surfaces of the drum. The flare of the inlet and the outlet passage also reduces the vertical end wall area with which the clothes or articles may come 35 into contact and thus reduces the liability of overheating and scorching.

Hot air is blown by a suitable ventilator through inlet and outlet pipes 5 and through the axially arranged air chambers 6. In order to force the air directly into and out of the 40 drum 2 through the tapered passages 3 a flange 7 is arranged on each end of the drum and each flange cooperates with a stationary close-fitting flange 8 fastened to the inner end of the casing 1. The closure effected in this manner prevents 45 considerable quantities of air from passing around the drum and casing and directs the stream of air through the interior of the drum.

The drum, which rotates slowly during the 50 passage of air, should be only partially filled with the articles treated so that the latter are continuously shifted during the rotation of the drum and continuously offer new surfaces to the stream of drying air. The enlarged air passages 3 serve as terminals for the direct passage 55

of the air through the drum; very little air escapes to circulate in the channel intermediate the drum and casing and the perforations in the cylindrical wall serve only to permit the entrance and discharge of the washing fluid during the cleaning operation.

The cooling action produced by evaporation of the solvent and the fact that there is no prolonged contact between the sheet metal walls 10 and the articles being treated, prevent damage to the latter even when the air enters the drum in a very hot state.

The washing machine shown in Figs. 3 and 4 has a large annular passage 13 for the stream 15 of air in an end wall of the drum 12. This passage is widened toward the interior of the drum and is provided with radial bars 14. Passage 13 differs from passages 3 (Figs. 1 and 2) in that it is spaced from the axis of the drum. This 20 arrangement facilitates the distribution of air and the connection with pipe 15 fastened to the end of casing 11 is simplified by the elimination of the special air chamber 6 of Fig. 1. Flanges 17-18, which span the space intermediate the drum and casing, provide an enclosed connecting conduit for direct passage of air. Flanges 21-28 adjacent the outer periphery of 25 the drum also prevent leakage, and wasteful circulation of the air in the channel intermediate 30 the drum and casing.

It will be apparent that the opposite end of the drum may be provided with a passage similar to passage 13, or one of the passages 3 shown in Fig. 1. In the embodiment illustrated, however, the other terminal for the direct passage 35 of the air through the drum is similar to that shown in my copending application Ser. No. 632,947 previously mentioned.

Regardless of the direction of flow of circulation of air is substantially completely confined 40 within the drum and very little heat is dissipated in the channel intermediate the drum and casing. Thus, assuming pipe 15, flange 18 and opening 13 as comprising the inlet, and perforations 20 and vent 21 as comprising the outlet, 45 very little air will escape through the usual widely spaced perforations 19 because of the

greater draft adjacent the closely spaced perforations 20 opposite vent 21. Assuming pipe 21 to be the inlet, the air will traverse the channel between this pipe and drum 12 in a direct line and substantially all of the air will enter 5 the drum through perforations 20 and be discharged through opening 13, flange 18 and pipe 15. This is so because there is no air outlet from the channel other than through the drum.

During the washing operation the closed casing 10 is partially filled with any desired type of washing fluid, such for instance as benzine, ethylene trichloride, carbon tetrachloride and the like.

The drying medium likewise may be of any suitable or convenient type. Thus I may use hot 15 air or other gas for removing the solvent residue and for drying the cleaned articles. Washing fluids such as benzine, which form an explosive mixture with air, can be removed by an inert gas as carbon dioxide or nitrogen. 20

The drawing does not show parts of the cleaning plant which form no part of my invention, such as ventilators or other means for circulating the hot air, coolers, heaters etc., as they may be employed in any one of the conventional 25 forms. Neither have I shown all forms of my invention which is capable of various modifications and adaptations within the scope of the appended claim.

The invention claimed is:

Apparatus for chemically cleaning fabrics, 30 textiles and the like, comprising a casing, a rotatable perforated drum in said casing adapted to contain articles to be cleaned, said drum having at one end means for admitting gases and 35 distributing same throughout substantially the entire interior of the drum and having at the other end means for withdrawing gases from substantially the entire interior of the drum, one of said means comprising a stationary passage 40 in the end of said casing eccentric with the adjacent end wall of the drum and an annular passage in the adjacent end wall of the drum communicating with said stationary passage as the drum is rotated, said annular passage being 45 flared longitudinally toward the interior of the drum.
